LIGHTER

Walter Spruegel and Walter W. Riedel, Dayton,
Ohio, assignors to General Motors Corporation,
Detroit, Mich., a corporation of Delaware

Application April 5, 1933, Serial No. 664,472

12 Claims. (Cl. 67—7.1)

This invention relates to lighters.

Conventional lighters contain a wad of fuel absorbing material such as cotton and the fuel is drawn therefrom by a wick. The disadvantage attached to this type of lighter resides in the fact that the wick draws only part of the fuel which is absorbed in the wad and after the dampness of the wad drops to a certain degree, the capillary attraction of the wick is insufficient to draw fuel from the wad. Naturally the lighter has to be refueled after a comparatively short time which is highly inconvenient to the user.

It is an object of the present invention to provide a lighter capable of being used over an extended period of time without refueling.

Another object of the present invention is to provide a lighter containing a supply of fluid in liquid form, which cannot be spilled from said lighter, regardless of the position in which it is carried.

Further objects and advantages of the present invention will be apparent from the following description, reference being had to the accompanying drawings wherein a preferred embodiment of one form of the present invention is clearly shown.

In the drawings:

Fig. 1 shows a cross sectional view of a lighter embodying the present invention. This view is a section taken on the line 1—1 of Fig. 3.

Fig. 2 is a sectional view taken on the line 2—2 of Fig. 1.

Fig. 3 is a sectional view taken on the line 3—3 of Fig. 1.

Fig. 4 is a section view similar to Fig. 1 showing, however, the lighter in inverted position. This view is a section taken on line 4—4 of Fig. 3.

Fig. 5 is a sectional view of the lighter in another inverted position.

Fig. 5a is a sectional view of the lighter in still another inverted position.

Fig. 6 is a cross-sectional view of a lighter incorporating a modification. This section is taken on line 6—6 of Fig. 7.

Fig. 7 is a sectional view taken on the line 7—7 of Fig. 6.

Fig. 8 is a cross sectional view similar to Fig. 6, showing the modified lighter in an inverted position, however.

Fig. 9 is a fragmentary view looking in the direction of arrows 9—9 in Fig. 6.

Fig. 10 is a cross sectional view of a lighter incorporating another modification. This section is taken on line 10—10 of Fig. 11.

Fig. 11 is a sectional view taken on the line 11—11 of Fig. 10.

Referring to the drawings, the reference numeral 20 represents a casing composed of a bottom 21, a top 22, and side walls 23. The casing may be assembled from parts in any suitable manner. Braced or otherwise secured to the top 22 of the casing is a tubular member 25 which extends deep into the casing and whose lower end adjacent the bottom 21 of the casing is closed by a cap 26. This tubular member receives a wick 27 whose one end extends slightly beyond the open end of tubular member 25. An opening 28 extends through the cap 26 and tubular member 25 and provides the sole communication between the wick 27 and the interior of the casing 20. Any suitable fuel 29 in liquid form is introduced into the casing 20 through a funnel 30 which is braced at 31 to a depressed portion 32 of a side wall 23 of the casing and extends through a hole 33 in said side wall into the interior of the casing. Funnel 30 is internally threaded at 34 and receives a plug 35 whose end 36 is externally tapered and adapted to seal the internally tapered entrance 31 of the funnel when the plug is properly threaded therein.

Any conventional ignition mechanism may be provided on the top 22 of casing 20. Figs. 1 and 2 illustrate an example of such a conventional ignition mechanism. A flint 40 is slidable longitudinally in a short tube 41 and permanently urged by a spring 42 in tube 41 against a ratchet disc 43 made of steel which is rotatable in unison with a larger wheel 45 rotatably supported and adapted to be manually rotated in order to rotate ratchet disc 43 relative to the flint 40 whereby a spark is produced which is directed toward the exposed end of wick 27. Tube 41 is mounted on a short column 46 which is attached in any suitable manner to the top 22 of the casing. Any suitable structure 47 is pivotally mounted at 48 to an upright 49, attached in any suitable manner to the top 22 of the casing, and covers the ratchet disc 43 and the exposed end of wick 27 when said structure is in the position shown in Figs. 1 and 2. Embracing that end of the tubular member 25 which extends beyond the top 22 of the casing is an externally tapered sleeve 50 which cooperates with the internally tapered cap 51 of structure 47 to prevent the escape of fuel vapor accumulating at the exposed end of the wick.

As shown in Fig. 2, that portion of the tubular member 25 which extends beyond the top 22 of the casing is located to the left of the center plane A—A in order to accommodate the ignition

mechanism. It is, however, imperative that the entrance hole 28 be located to the right of the center plane A—A for a reason that appears obvious later; therefore, the tubular member 25 is slightly bent as shown in Figs. 2 and 3. The exposed end of the wick is also located to the left of center plane B—B (see Fig. 1) to accommodate the ignition mechanism. It is, however, imperative that the entrance hole 28 be located to the right of center plane B—B for a reason that appears obvious later, therefore, the tubular member is also curved as shown in Fig. 1. More particularly, entrance hole 28 is so located that the fuel supply in the casing can under no circumstances flood the entire wick, the capillary attraction of wick 27 being solely relied upon in any position of the casing to convey fuel from the supply to the exposed wick portion. As long as the entrance hole 28 dips into the fuel supply a substantial portion of the wick is always above the fuel level. The maximum amount of fuel supply in the casing is naturally of great importance for the proper location of entrance hole 28. Regardless of any shape the casing may assume, the following course will always lead to the proper location of said entrance hole. The location of that portion of the tubular member 25 which extends beyond the casing is generally known and it is also known what minimum portion of the wick has to extend above the fuel level regardless of any position the casing may assume. The casing is inverted into a most unfavorable position in which said predetermined minimum portion of the tubular member 25 extends above an assumed maximum fuel level and the entrance hole 28 will have to be located substantially in said fuel level. Upon inversion of the casing from said most unfavorable position, the portion of the tubular member above the fuel level may immerse into the fuel supply but concurrently therewith the entrance hole 28 moves away from the fuel supply and cuts off communication between the latter and the wick, or the portion of the tubular member above the fuel level will increase and concurrently therewith the entrance hole will dip deeper into the fuel supply. In the present form of the casing, there are two most unfavorable positions that have to be taken into account, these two positions being illustrated in Figs. 2 and 5, respectively. In Fig. 2 the casing must be assumed to be in a position in which the fuel assumes the dot-and-dash position. It will be noted that as long as the entrance hole 28 is located substantially in the maximum fuel levels shown there, the wick will never be flooded entirely, it takes at least the capillary attraction of that portion of the wick extending above these illustrated fuel levels in order to convey fuel to the exposed wick portion. Supposing the casing 20 assumes the position shown in Fig. 5a then capillary attraction of the wick has to convey fuel from the fuel level to the highest portion of the wick above the fuel level. Having determined the exact location of the entrance hole in the tubular member 25 and having also determined the maximum fuel supply in the casing 20, the funnel is extended to the maximum fuel level when the casing is in the position shown in Fig. 4 so that said funnel serves also as an indicator for proper refueling of the lighter, the same being properly refueled when the fuel level reaches the entrance of the funnel 30. Further pouring of fuel into the funnel 30 would not result in an appreciable rise of the fuel level because the air in the casing above said level is trapped and the funnel would merely overflow. The fun-

nel therefore renders a complete filling of the casing impossible and even prevents a filling of the casing beyond a predetermined maximum fuel amount therein. Since the position of the lighter shown in Fig. 1 is that position in which the lighter is used, the entrance hole 28 is naturally located close to the bottom 21 of the casing in order to make satisfactory use even of a slight fuel supply. The long tubular member effectively prevents an explosion of the lighter, a striking back of the flame throughout the entire length of said tubular member is impossible.

The modification disclosed in Figs. 6 to 9, inclusive, comprises a tubular member 60 to which is braced another member 61 containing a wick 62 arranged in the convolute fashion disclosed in Figs. 6 and 8. One end of said wick extends through tubular member 60 and the other end thereof is firmly held by a tongue 63 of member 61 which is bent over said other wick end. Whenever necessary, the user will pull out the wick slightly at the free end of tubular member 60 and before the wick convolutions in member 60 are rolled open by such pulling out of the wick end, a long period of time during which the lighter is used will elapse. However, the end held by tongue 63 will not give way under the pull of the user, therefore the wick 62 always extends through the entire length of tubular member 60 and the latter is long enough effectively to prevent a striking back of the flame into fuel supply. Member 61 is provided with an opening 64 which is cut out in order to form the already explained tongue 63. Opening 64 is located at a point inside the case where the maximum fuel supply will never flood the entire wick regardless of any position the casing may assume. Naturally the same course as earlier described will be taken in order properly to locate opening 64.

The modification disclosed in Figs. 10 and 11 comprises a tubular member 70 which is braced or otherwise attached to the top 71 and also to an internal lug 72 of the bottom 73 of a casing 74. This tubular member contains a wick 75. A plug 76 and gasket 77 seal the internal lug 72. An opening 78 in the tubular member 70 which provides the sole communication between the wick and the fuel supply 79 is located within the casing 74 in the manner explained earlier so that the maximum fuel supply cannot flood the wick in any position of the housing. The wick, after having been used up to a certain extent may readily be replaced by removing plug 76 and inserting a new wick into the tubular member 70.

While the form of embodiment of the present invention as herein disclosed, constitutes a preferred form, it is to be understood that other forms might be adopted, all coming within the scope of the claims which follow.

What is claimed is as follows:

1. A lighter comprising, in combination, a substantially rectangular casing for containing a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending from said wall eccentrically thereof into the casing; and a tubular member surrounding the wick and having an opening providing the sole communication between the wick and the fuel supply, said opening being so located with respect to the casing that the fuel supply cannot flood the entire wick.

regardless of any position the casing may assume.

2. A lighter comprising, in combination, a substantially rectangular casing for containing a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending from said wall eccentrically thereof into the casing; and a tubular member surrounding the wick and having an open end adjacent the ignition mechanism and an orificed bottom in the casing which provides the sole communication between the interior of the tubular member and the interior of the casing, said tubular member being so located with respect to the casing that a substantial length of the tubular member is above the fuel level regardless of any position the casing may assume.

3. A lighter comprising in combination, a casing for containing a supply of fuel in liquid form, said casing having a top wall and an opposite bottom wall; means carried by the casing for introducing therein a predetermined maximum fuel supply which is less than the capacity of the casing; means for sealing the introduction means; ignition mechanism on the top wall of the casing; a wick associated with the ignition mechanism and extending from the top wall eccentrically thereof into the casing; and a tubular member secured to the top wall and surrounding the wick and having an open end adjacent the ignition mechanism and an orificed bottom adjacent the bottom wall of the casing, said orificed bottom providing the sole communication between the interior of the tubular member and the interior of the casing, and said tubular member being so located with respect to the casing that a substantial length of the tubular member is above the fuel level regardless of any position the casing may assume.

4. A lighter comprising, in combination, a substantially rectangular casing for containing a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending from said wall eccentrically thereof into the casing; and a member secured to said wall and surrounding a part of the wick adjacent the ignition mechanism and containing the remainder of the wick in convolutions, the end of which is attached to the member by a tongue punched therefrom, the opening in the member resulting from the punching of the tongue providing the sole communication between the interior of the casing and the interior of the member and being so located with respect to the casing that the fuel supply cannot flood the entire wick regardless of any position the casing may assume.

5. A lighter comprising in combination, a casing for containing a supply of fuel in liquid form, said casing having a top wall and an opposite bottom wall; means carried by the casing for introducing therein a predetermined maximum fuel supply which is less than the capacity of the casing; means for sealing the introduction means; ignition mechanism on the top wall of the casing; a wick associated with the ignition mechanism and extending from the top wall eccentrically thereof into the casing; and a member se-

cured to the top wall, the open end of the member being adjacent the ignition mechanism and the bottom thereof being adjacent the bottom wall of the casing, said member surrounding a part of the wick adjacent the ignition mechanism and containing the remainder of the wick in convolutions the end of which is attached to the member by a tongue punched from the bottom of said member, the opening in the member resulting from the punching of the tongue providing the sole communication between the interior of the casing and the interior of the member and being so located with respect to the casing that the fuel supply cannot flood the entire wick regardless of any position the casing may assume.

6. A lighter comprising, in combination, a casing for containing a supply of fuel in liquid form, said casing having a top wall and a bottom wall provided with an opening; means carried by the casing for introducing therein a predetermined maximum fuel supply which is less than the capacity of the casing; means for sealing the introduction means; ignition mechanism on the top wall of the casing; a wick associated with the ignition mechanism and extending from the top wall eccentrically thereof into the casing; a tubular member surrounding the wick, one open end of the member extending through the top wall of the casing adjacent the ignition mechanism and the other open end thereof being received by the opening in the bottom wall of the casing, said member being provided with an orifice providing the sole communication between the interior of the casing and the interior of said member and being so located with respect to the casing that the fuel supply cannot flood the entire wick regardless of any position the casing may assume; and means for sealing the opening in the bottom of the casing.

7. A lighter comprising, in combination, a substantially rectangular casing for holding a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending into the casing from a point remote from the center of said casing wall; and a tubular member secured to said casing wall and surrounding the wick and having an orificed bottom which provides the sole communication between the interiors of the tubular member and the casing, said tubular member being curved so as to locate the orifice thereof within the casing in such manner that the fuel supply cannot flood the entire wick regardless of any position the casing may assume.

8. A lighter comprising, in combination, a substantially rectangular casing for holding a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending into the casing from a point remote from the center of said casing wall; and a tubular member secured to said casing wall and surrounding the wick and having an orificed bottom which provides the sole communication between the interiors of the tubular member and the casing, said tubular member being curved so that a substantial length of the same is above

- the fuel level regardless of any position the casing may assume.
9. A lighter comprising, in combination, a substantially rectangular casing for holding a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending into the casing from a point near one corner of said casing wall; and a tubular member secured to said casing wall and surrounding the wick and having an orificed bottom which provides the sole communication between the interior of the tubular member and the interior of the casing, said tubular member curving toward a corner of the casing diagonally opposite the first mentioned corner so as to locate the orifice thereof within the casing in such manner that the fuel supply cannot flood the entire wick regardless of any position the casing may assume.
10. A lighter comprising, in combination, a substantially rectangular casing for holding a supply of fuel in liquid form; means carried by the casing for introducing therein a predetermined maximum fuel supply which is less than the capacity of the casing; means for sealing the introduction means; ignition mechanism on a wall of the casing; a wick associated with the ignition mechanism and extending into the casing from a point near one corner of said casing wall; and a tubular member secured to said casing wall and surrounding the wick and having an orificed bottom which provides the sole communication between the interior of the tubular member and the interior of the casing, said tubular member curving toward a corner of the casing diagonally opposite the first mentioned corner so that a substantial length of the tubular member is above
- the fuel level regardless of any position the casing may assume.
11. A lighter comprising, in combination, a casing for containing a supply of fuel in liquid form, said casing having at least one flat wall; means carried by the casing for introducing therein a predetermined maximum fuel supply which is less than the capacity of the casing, means for sealing the introduction means; ignition mechanism on said one flat wall of the casing; a wick associated with the ignition mechanism and extending from said one flat wall eccentrically thereof into the casing; and a tubular member surrounding the wick and having an opening providing the sole communication between the wick and the fuel supply, said opening being so located with respect to the casing that the fuel supply cannot flood the entire wick regardless of any position the casing may assume.
12. A lighter comprising, in combination, a casing for containing a supply of fuel in liquid form, said casing having at least one flat wall; means carried by the casing for introducing therein a predetermined maximum fuel supply which is less than the capacity of the casing; means for sealing the introduction means; ignition mechanism on said one flat wall of the casing; a wick associated with the ignition mechanism and extending from said one flat wall eccentrically thereof into the casing; and a tubular member surrounding the wick and having an open end adjacent the ignition mechanism and an orificed bottom in the casing which provides the sole communication between the interior of the tubular member and the interior of the casing, said tubular member being so located with respect to the casing that a substantial length of the tubular member is above the fuel level regardless of any position the casing may assume.
